UNITED STATES PATENT OFFICE.

EDWARD L. BENEDICT, OF BALTIMORE, MARYLAND, ASSIGNOR OF ONE-HALF TO
ORVILLE O. ROBINSON, OF BALTIMORE COUNTY, MARYLAND.

BUILDING STRUCTURE.

Specification of Letters Patent. Patented July 29, 1919.

1,311,486.

Application filed December 20, 1918. Serial No. 267,602.

To all whom it may concern:

Be it known that I, EDWARD L. BENEDICT, a citizen of the United States, residing at Baltimore, in the State of Maryland, have 5 invented certain new and useful Improvements in Building Structures, of which the following is a specification.

This invention relates to metal building structures, and more particularly to a sheet 10 metal bar adapted for convenient attachment to other similar bars and usable as a unit in constructing the frame-work of metal buildings.

In the accompanying drawing,

15 Figure 1 is a perspective view of a sheet metal T-bar, partly broken away, embodying my improvements;

Fig. 2 is a similar view of one end of a sheet metal column adapted to make a right- 20 angled joint with the bar shown in Fig. 1;

Fig. 3 is a side elevation showing the joint formed by connecting the bars illustrated in the previously described figures;

25 Figs. 4 and 5 are detail perspective views illustrating the manner in which several bars may be connected in assembling the frame-work of a building, and,

Fig. 6 is an end elevation of an assemblage 30 of metal T-bars arranged to form a building frame.

Referring to Fig. 1 of the drawing, A represents a T-bar rolled from a sheet metal strip, the head 1 of the bar being formed from the central portion of the strip by 35 folding the strip longitudinally, as indicated at 2, and the web 3 is formed by bending the marginal portions of the strip outwardly, as indicated at 4, at right angles to the head. The bar thus comprises the 40 head 1, composed of a double thickness of sheet metal rolled substantially flat, and two parallel web portions 3^a, spaced a short distance apart, as shown. For the purpose of readily assembling and securing a plurality of these bars in a building structure, 45 I punch one or more slots or kerfs 5 in the head of the bar, in alinement with the space or channel between the web portions 3^a, and the length of each slot is substantially equal 50 to the width of the web portion of the bar. These slots are punched after the bar has been rolled by laying the head of the bar on the punching machine and passing a flat

punch downward between the web portions, the latter serving as guides, so that the slot, 55 when formed, is alined with the channel between the web portions. Such slots may be formed at various points in the head, but for most purposes, the bar is slotted in the ends only, as shown in Fig. 1. 60

The manner in which the bar is used in building construction is illustrated in Fig. 6, and the joints or connections between the bars are illustrated more in detail in Figs. 2-5, inclusive. 65

In Fig. 6, two of the sheet metal T-bars, arranged as supporting columns, are shown at 6, and to the upper ends of these columns is connected a truss bar 7. Above the truss bar are rafters 8, struts 9, and ties 10, all 70 composed of the sheet metal T-bars and connected together to form a roof structure. In Fig. 2 is shown the upper end of one of the columns 6, in which the head portion 1^a of the bar is sheared from the web portions 75 for a distance substantially equal to the width of the bar, and the head portion is bent outwardly at right angles to the bar, as shown, in order to provide a support for the truss beam 7. As shown in Fig. 3, and 80 also in Fig. 4, the column and truss beam are connected together by passing the slotted end of the truss beam down over the web of the column until the truss beam rests upon the lateral support 1^a. The slot in the 85 truss beam being substantially equal in length to the width of the web of the column, and the support 1^a being below the end of the column a distance approximately equal to the depth of the truss beam, it will 90 be evident that the parts will make a substantially flush joint when placed together. Bolt holes *b*, properly positioned, are punched in the webs before the parts are 95 assembled, and bolts *c* secure the webs together. Other bolts *d* pass through the head of the truss bar and through perforations *e* in the lateral support 1^a and secure the truss bar to said support.

In Fig. 4, the manner of connecting one 100 of the rafters to the column and truss bar is illustrated. In this figure, the column and truss bar are connected as shown in Fig. 3, and the rafter 8 is joined to the webs of both of said bars by passing the web portions 105 3^a of the rafter between the web por-

tions of the truss and the column. When the bolts *c* are inserted, it will be seen that they bind the webs of the three bars together, and an additional bolt *c'*, passing through the webs of the truss bar and rafter, forms a further securing means.

Fig. 5 illustrates the connection between the truss bar and a strut 9 and tie 10. It will be seen that by simply placing the 10 lower end of the strut or tie so that the slot 5 therein will straddle the web of the truss bar, and then bolting the webs of the bars together, firm and secure joints are quickly made. In Fig. 5, the web of the 15 strut 9 straddles the web of the truss bar and the web of the tie 10 is slightly spread at the bottom and straddles the web of the truss bar as well as the strut, and the webs of the three bars are connected by the bolts 20 *f*. In the roofing structure shown in the drawing, it will be understood that the struts 9 are slotted at both ends and straddle the webs of the bars 7 and 8, and the ties 10 are also slotted at both ends. The 25 upper ends of the ties straddle a metal gusset-plate 11, which fits between the web portions of the rafters 8 at their upper ends

and is bolted to said web portions and to the ties.

What I claim is:

1. In a building structure, a T-beam comprising a sheet metal strip having its central portion folded upon itself and flattened to form a head and having its marginal portions bent outwardly, from the head, parallel with one another, to form a web, said marginal portions spaced apart to provide a channel therebetween, the head of the beam having a longitudinal slot in line with the channel adapted to receive the web of a similar beam. 30

2. In a building structure, a T-beam comprising a sheet metal strip having its central portion folded upon itself and flattened to form a head and having its marginal portions bent outwardly from the head, parallel with one another, to form a web, said marginal portions spaced apart to provide a channel therebetween, the head of the beam having a longitudinal slot in each end, said 45 slots being in line with the channel and adapted to receive the webs of similar beams. 50

In testimony whereof I affix my signature.
EDWARD L. BENEDICT.
